(No Model.)

G. C. FORBES.
CHURN POWER.

No. 553,457.

Patented Jan. 21, 1896.

UNITED STATES PATENT OFFICE.

GROVES C. FORBES, OF HOMER, GEORGIA.

CHURN-POWER.

SPECIFICATION forming part of Letters Patent No. 553,457, dated January 21, 1896.

Application filed September 9, 1895. Serial No. 561,947. (No model.)

To all whom it may concern:

Be it known that I, GROVES C. FORBES, a citizen of the United States, residing at Homer, in the county of Banks and State of Georgia, have invented certain new and useful Improvements in Churn-Powers; and I do hereby declare the following to be a full, clear, and exact description of the invention, such as will enable others skilled in the art to 10 which it appertains to make and use the same.

My invention relates to improvements in churn-powers; and it consists of certain novel features hereinafter described and claimed.

My invention also consists in certain novel 15 combinations and arrangements of parts hereinafter described and claimed.

Reference is had to the accompanying drawings, in which the same parts are indicated by the same letters throughout the several views.

20 Figure 1 is a side elevation of the apparatus. Fig. 2 is a section along the line 2 2 of Fig. 1, and looking to the right; and Fig. 3 represents a section along the broken line 3 3 of Fig. 1, and looking down, the driving- 25 wheel being shown in plan and not in section.

A represents the platform, preferably a heavy board, on which the framework of the machine and the churn are mounted.

A' and A² represent uprights, the former 30 being provided with a guide-slat a' secured thereto and at a short distance therefrom, between which and the said uprights A' is a guide groove or slot a⁰. Instead of a slat a' a round rod or wire may be used if desired, 35 whereby less friction is occasioned. The opposite upright A² is provided with guide-plates a², in which slides the guide-rod C, attached by means of the clamp-plate B' to the reciprocating cross-piece B, which is secured 40 by means of the clamp E to the handle D of the churn. This cross-piece B is slotted, as at b⁰, to receive the clamp-screw e, which binds together and at the same time clamps on the said cross-piece the two parts e' and e² of the 45 clamp E. Thus it will be seen that the said clamp may be moved out or in on the said cross-piece, and thus adjustment may be had for the diameter of the churn, with large churning it being necessary to have the handle 50 farther from the upright A² than with the small churn.

The handle D is held in the groove e⁰, made

partly in each of the members e' and e² of the clamp E. The handle D carries a fly-brush G made of a bent-wire clip g', or a clip of any 55 suitable resilient material, adapted to slip over and to be held on the said handle, from which clip are suspended a plurality of strings, yarns or papers, forming a depending fringe which plays up and down as the churn rises 60 and falls and thus effectually prevents a settling of flies upon either the said handle or upon the top of the churn.

Reciprocating motion is given to the cross-piece B by means of the downwardly-extending arm B², to which is pivotally connected the rod H, pivoted at h in one of the holes h⁰ in the crank K, which is journaled at k and provided with a counterpoise-arm K'; or the connecting-rod H may be pivoted directly to 65 the cross-piece B, and the downwardly-projecting arm B² may be omitted. This crank K is revolved by the shaft M, which is driven by the sprocket-wheel M' and chain N from the driving-wheel P, which is driven by the 70 hand-crank p.

It will be seen that the stroke of the churn-dasher may be varied by moving the pivot-pin h out or in on the crank K.

In order to stiffen the frame of the machine 80 triangular brace-boards A³ are preferably secured to the uprights A' and A² and to the platform A.

The various advantages of the herein-described construction will readily suggest 85 themselves to any practical mind.

Having thus described my invention, what I claim, and desire to secure by Letters Patent of the United States, is—

1. In a churn power the combination with 90 the upright A' provided with a guide slat a', the upright A² provided with guides a², the reciprocating beam B passing in the slot a⁰ and carrying the clamp plate B' the guide rod C secured between said clamp plate B' 95 and said reciprocating beam and passing through said guides a² and a clamp for securing the churn handle to said reciprocating beam, substantially as described.

2. In a churn power, the combination with 100 the upright A' provided with a guide slat a', the upright A² provided with guides a², the reciprocating beam B passing in the slot a⁰, between said upright A' and the guide slat a',

the guide rod C secured to said beam and passing through said guides α^2 , and the clamp E consisting of the two members e^2 and e' and the clamp screw e adjustably connected to 5 said beam and clamping the two parts together, substantially as and for the purposes described.

In testimony whereof I affix my signature in presence of two witnesses.

GROVES C. FORBES.
